MATCH

Harry Brodsky, Philadelphia, Pa.

Application January 13, 1936, Serial No. 58,801

5 Claims. (Cl. 40—2)

This invention relates to matches, and it relates more particularly to a novel form of match especially adapted for use as an advertising device or the like.

5 The principal object of the present invention is to provide a match having concealed indicia thereon, which concealed indicia will be rendered visible by the ignition and burning of the match in the usual manner.

10 With the foregoing object in view, the invention also contemplates as a preferred form, a match having indicia initially visible thereon, which will be disseminated or dissipated upon the burning of the match and the concealed 15 indicia brought into view in place thereof.

15 The invention is particularly adaptable for use in connection with the paper matches at present in common use, and more particularly in connection with the paper matches of larger sizes 20 which have more recently appeared on the market.

25 It should of course be understood that the description and drawing herein contained are illustrative merely and that the invention is susceptible of embodiment in a variety of forms.

30 The nature and characteristic features of the invention will be more readily understood from the following description, taken in connection with the accompanying drawing forming part 35 hereof, in which:

Figure 1 is a plan view, enlarged of a match embodying the main features of the preferred form of the present invention, the same being shown in its condition prior to ignition and 40 burning;

35 Fig. 2 is a similar view, showing the same match after the same has been burned to bring out the concealed indicia thereon; and

45 Fig. 3 is a longitudinal sectional view, greatly enlarged, of a portion of the match showing the component parts of the preferred form thereof.

Referring to the drawing, in the particular embodiment of the invention therein shown, 50 10 is a match splint which is preferably made of paper or the like. The paper of which the splint is made is preferably either of a special composition or is so treated that upon the burning thereof the same will not be unduly twisted, distorted, discolored, or reduced to a fragile ash.

55 For example, the paper may have impregnated therein various chemical substances for the aforesaid purpose, such as barium sulphate, magnesium carbonate, magnesium oxide, or zinc oxide. Various other substances may also be 60 found suitable for this purpose, and in some

instances the paper composition may be merely varied by the addition of a large quantity of clay in the pulp.

In any event the desired impregnation of the paper may take place either by the incorporation of the desired chemical or other material directly in the pulp during the making of the paper of which the match splints are made, or the formed paper may be treated by immersion of the paper in suitable liquids in which the desired impregnating material is in solution or suspension, or the material may be applied to the surface of the paper for this purpose. 5

Match splints composed or treated as aforesaid may have imprinted thereon the concealed 15 indicia which is to be rendered visible upon the burning of the match. Various materials may be found suitable for this imprinting of the concealed indicia. Any material which will remain discernible when the match is burned will 20 be suitable. Preferably ceramic pigments are employed for this purpose, as the burning of the match has the effect of setting the same. The imprinting of the concealed indicia is indicated at 11. 25

After the concealed indicia 11 is imprinted on the match splints 10 the same are coated as at 12 with a suitable material for the purpose of initially concealing said indicia. The coating material 12 may comprise various substances, the essential being that the same will either be combustible in the flame of the match, or be disseminated by the heat thereof, or rendered transparent by said heat. 30

If the concealing coat is to be of the type 35 which is combustible in the flame of the match, various heavy paraffins, waxes, etc. may be used, as these substances leave little or no ash upon burning. Of course, these may be applied to the match splints either in a melted condition, 40 or by the use of a suitable solvent which will render them sufficiently liquid to be readily applied to the splints.

The concealing coat may comprise certain of 45 the metallic oxides, lead oxide and mercuric oxide being particularly adaptable, the same being applied in a suitable vehicle such as linseed oil or the like. If mercuric oxide is used, the same will be completely volatilized upon the burning of the match, whereas in the case of lead oxide the same will be reduced to tiny beads of metallic lead which will permit the concealed 50 indicia to be seen, at the same time imparting an ornamental effect of its own.

A concealing coat which has been found to 55

be particularly adaptable may comprise any of the well known mixtures, which, upon the burning of the match, will form a transparent glaze through which the concealed indicia will be 5 visible.

After the concealing coating 12 is placed on the splint over the concealed indicia, an overprinting 13 of visible indicia may be placed thereon. The ink or other material employed 10 for the overprinting 13 should be of a combustible type, or capable of being disseminated by the heat engendered by the burning of the match. Aniline dyes in a linseed oil vehicle, or in a paraffin, wax, or heavy grease body, will be 15 found quite suitable for this purpose, or the metallic oxides may be used in a suitable vehicle such as linseed oil.

In the use of the match it is only necessary for the user thereof to strike the same in the 20 ordinary manner, whereupon during the burning of the match the concealing coating as well as any overprinting which may be placed thereon will be consumed, disseminated, or transformed, by the heat of the match as the same 25 burns. In this manner the concealed indicia will be rendered visible.

It will be seen that there is provided a novel form of match which will be of peculiar value for advertising purposes in that the curiosity 30 of the user will be excited, and in this manner the message conveyed by the concealed indicia will be definitely impressed upon his mind.

It will, of course, be understood that the matches of the present invention may be used 35 for purposes other than advertising; for example, suitable games may be worked out in connection therewith.

It should also be understood that while the invention has only been illustrated in connection 40 with the splint of the match, the same is also applicable to the head portion thereof.

I claim:

1. A match having indicia imprinted thereon,

and a coating for initially concealing said indicia which would otherwise be visible, said concealing coating being alterable by the burning of the match so that the aforesaid indicia will be rendered visible when the match is burned. 5

2. A match having indicia imprinted thereon, a concealing coating over said indicia, said concealing coating being alterable by the burning of the match whereby the aforesaid indicia will be rendered visible, and an overprinting of 10 initially visible indicia disseminatable upon the burning of the match.

3. A match having the splint thereof treated to minimize distortion, discoloration and reduction thereof to a fragile ash, indicia imprinted 15 on said prepared splint, and a coating for initially concealing said indicia, which would otherwise be visible, said concealing coating being alterable by the burning of the match so that the aforesaid indicia will be rendered visible when 20 the match is burned.

4. A match having the splint thereof preliminarily prepared to minimize distortion, discoloration and reduction thereof to a fragile ash, 25 indicia imprinted on said prepared splint, and a coating for initially concealing said indicia which would otherwise be visible, said concealing coating being alterable by the burning of the match so that the aforesaid indicia will be rendered visible when the match is burned. 30

5. A match having the splint thereof preliminarily prepared to minimize distortion, discoloration and reduction thereof to a fragile ash, indicia imprinted on said prepared splint, a concealed coating over said indicia, said concealing 35 coating being alterable by the burning of the match whereby the aforesaid indicia will be rendered visible, and an overprinting of initially visible indicia disseminatable upon the burning of the match.

HARRY BRODSKY. 40
